UNITED STATES PATENT OFFICE.

ROBERT E. McELDOWNNEY, OF NEW MARTINSVILLE, WEST VIRGINIA, ASSIGNOR TO
NEW MARTINSVILLE GLASS MFG. CO., OF NEW MARTINSVILLE, WEST VIRGINIA,
A CORPORATION OF WEST VIRGINIA.

DESIGN FOR A SANDWICH PLATE OR SIMILAR ARTICLE.

Application filed February 8, 1928. Serial No. 25,263. Term of patent 3½ years.

To all whom it may concern.

Be it known that I, ROBERT E. McELDOWNNEY, a citizen of the United States, residing at New Martinsville, in the county of Wetzel, State of West Virginia, have invented a new original, and ornamental Design for a Sandwich Plate or Similar Article, of which the following is a specification, reference being had to the accompanying drawing, forming part thereof.

Figure 1 is a plan view of a sandwich plate or similar article, showing my new design.

Figure 2 is a side elevation of Figure 1.

I claim:—

The ornamental design for a sandwich plate or similar article, as shown.

ROBERT E. McELDOWNNEY.
